C. J. OWENS

Des. 126,269

FLAG OR THE LIKE

Filed Jan. 16, 1941

Clarence Julian Owens

Inventor

UNITED STATES PATENT OFFICE

126,269

DESIGN FOR A FLAG OR THE LIKE

Clarence Julian Owens, Washington, D. C.

Application January 16, 1941, Serial No. 98,134

Term of patent 7 years

To all whom it may concern:

Be it known that I, Clarence Julian Owens, a citizen of the United States, residing at Washington, District of Columbia, have invented a new, original, and ornamental Design for a Flag or the like, of which the following is a specification, reference being had to the accompanying drawing, forming part thereof.

The figure is a plan view of a flag or the like, showing my design.

I claim:

The ornamental design for a flag or the like, substantially as shown.
